UNITED STATES PATENT OFFICE.

JOHN BAPTIST BROWN, OF AKRON, OHIO.

AUTOMATIC CUT-OFF FOR GAS.

SPECIFICATION forming part of Letters Patent No. 784,915, dated March 14, 1905.

Application filed January 9, 1904. Serial No. 188,371.

To all whom it may concern:

Be it known that I, JOHN BAPTIST BROWN, a citizen of the United States, residing at Akron, in the county of Summit and State 5 of Ohio, have invented new and useful Improvements in Automatic Cut-Offs for Gas, of which the following is a specification.

My invention relates to means for automatically cutting off the supply of gas in service-pipes when the pressure falls below a predetermined point, thereby avoiding a continued flow of gas after lights have been extinguished by reason of such fall in pressure, which fall may have been but temporary, permitting the 10 normal amount to escape from the burners at which the lights had been extinguished unless the gas was cut off as soon as the pressure fell.

My invention consists of the novel features 15 of construction and combination of parts hereinafter described, particularly pointed out in the claims, and shown in the accompanying drawings, in which—

Figure 1 is a perspective view of my device. Fig. 2 is a vertical section through the casing, the connecting-pipes being shown in section and the interior mechanism being shown in elevation. Fig. 3 is a horizontal section, a portion of the casing being broken 20 away, on the line 3 3 of Fig. 2.

In the drawings, A represents a casing, preferably cylindrical in form, A' a section of a service-pipe discharging into the casing A, and A'' a pipe-section leading from the casing, the casing being interposed between the sections of the service-pipe at any desired point. The casing A is divided horizontally into two portions, the lower portion forming the body of the casing and the upper portion 25 a top or cover, both portions being flanged, as shown at A³, the flanges resting adjacent each other and being secured together by suitable screws. Between the flanges is held a disk B of any desired material, thin copper 30 being preferred, which forms a horizontal partition in the casing. Secured to the bottom of the casing is a base-plate C, carrying at its ends vertically-arranged brackets C' and C'', forming guide-brackets through which 35 work a plunger-rod C³. An adjustable block

C⁴ is carried by the plunger-rod between the brackets, and a coiled spring C⁵, which encircles the plunger-rod C³, bears at one end against the block C⁴ and at its opposite end against the bracket C². The block C⁴ is held against longitudinal movement along the plunger-rod by means of a suitable set-screw, and the block can be adjusted to regulate the pressure exerted by the spring C⁵. At the forward end of the plunger-rod is arranged a valve D, the front face of which is covered with buckskin, as shown at D'. Flanged openings A⁴ are formed diametrically opposite each other in the sides of the casing, the sections of the service-pipe fitting in the flanges A⁵, and the plunger-rod 60 C³ works in alinement with these openings, one of which is adapted to be closed by the valve D cutting off the supply of gas to the pipe-section A², which supplies the burners. At its rear end the plunger-rod C³ is enlarged 65 and bifurcated, and in the bifurcated portion is arranged a roller C⁶, and adjacent the roller the plunger-rod carries a depending lug C⁷.

A lever E is pivoted intermediate its ends to the upper portion of the bracket C², and adjacent the rear end of the lever a curved recess is formed, as shown at E'. A rod F is secured at its upper end to the under face of the disk B, and preferably at the center of the disk and at its lower end the rod is pivoted to the forward end of the lever E.

Mounted on the top of the casing and centrally arranged is a cylindrical cap G, over which is threaded a cover or top piece G'. Centrally arranged upon and secured to the upper face of the disk B is a rod H, formed in two sections connected by links H', forming a universal joint, and the upper section of the rod H extends upward through the top of the casing A into the cap G. The upper end of the rod is threaded, and a nut H² is arranged on this threaded portion, while a coiled spring is arranged on the rod between the nut H² and the top of the casing A, the spring bearing at one end on the nut and at the opposite end on the top of the casing.

Extending through a boss J, formed in one side of the casing, is a rotatable shaft J', journaled at its inner end in a portion of the bracket C² and arranged at a right angle to

the plunger-rod C³. At its inner end the shaft J' carries a crank J², having a pin J³, which engages the lug C⁷ on the plunger-rod C³.

The operation of the cut-off is as follows:

- 5 A suitable hand-wheel J⁴ is arranged on the outer end of the shaft J', and by rotating same the rotation of the shaft rotates the crank, and the pin pressing on the lug draws back the plunger-rod C³, drawing back the
- 10 valve D and opening the entrance to the pipe-section A². The flow of gas being normal, it is obvious that there will be an equal pressure on each side of the valve and also an upward pressure on the disk B. The rearward
- 15 movement of the plunger-rod just described causes the roller, which had been resting in the recess E', to move out of said recess and lift the rear end of the lever E, while at the same time the pressure upward of the gas on
- 20 the disk B and the upward pressure of the spring H² on the nut H² also tends to draw upward the disk B. The said disk being elastic or springy, this upward movement of the central portion of the disk tends to lift the forward end of the lever E and depress the rear
- 25 end, the result being that the rear end bears with considerable pressure on the roller C⁶, counterbalancing the forward tendency given to the plunger-rod C³ by the spring C⁵ and holding it locked. Should, however, the pressure of the gas be reduced sufficiently, the spring C⁵ will overcome the locking effect due to the
- 30 combination of the pressures of the gas and spring H², and the plunger will move forward
- 35 and the valve will close the opening A¹. In this position the roller C⁶ will again be in engagement with the recess E', and when the pressure of the gas is restored to its normal degree the valve will still remain closed, as
- 40 there will be now an excess of pressure against the rear face of the valve, so that the pressure of the gas will now coöperate with the spring C⁵ to hold the valve closed. The valve will

remain closed until the device is again set by rotation of the hand-wheel J⁴.

Having thus fully described my invention, what I claim as new, and desire to secure by Letters Patent, is—

1. In a device of the kind described, a casing, a supply-pipe, a service-pipe leading from the casing, a spring-pressed valve adapted to close the inner end of the service-pipe, an elastic diaphragm, a lever operable by movement of the diaphragm and adapted to lock the valve in open or closed position, and a spring adapted to coöperate with pressure of the gas in lifting the diaphragm.

2. In a device of the kind described, a casing, supply and service pipes, a movable plunger, a valve carried thereby and adapted to close one of the pipes, an adjustable spring adapted to close the valve, a lever adapted to lock the plunger against movement, a diaphragm connected to said lever and adapted to be moved by pressure of the gas and to lift the lever, and a spring connected to the diaphragm and adapted to counterbalance the first-mentioned spring.

3. A device of the kind described comprising a casing, service and supply pipes, a plunger longitudinally movable, a valve carried by the plunger adapted to close the service-pipe, a spring adapted to force the plunger forward, a roller carried by the plunger, an elastic diaphragm arranged parallel with the plunger, a lever pivoted intermediate its end and adapted to be actuated by the diaphragm, one end of said lever resting on the roller, and being recessed adjacent said end, the roller engaging the said recess when the valve is closed, and a spring adapted to coöperate with gas-pressure in lifting the diaphragm.

JOHN BAPTIST BROWN.
